UNITED STATES PATENT OFFICE.

DAVID MOON, OF WALLA WALLA, WASHINGTON.

BOOK-TURNER.

SPECIFICATION forming part of Letters Patent No. 567,403, dated September 8, 1896.

Application filed February 19, 1896. Serial No. 570,890. (No model.)

To all whom it may concern:

Be it known that I, DAVID MOON, a citizen of the United States, residing at Walla Walla, in the county of Walla Walla and State of Washington, have invented certain new and useful Improvements in Book-Turners; and I do hereby declare the following to be a full, clear, and exact description of the invention, such as will enable others skilled in the art 10 to which it appertains to make and use the same.

This invention relates to certain new and useful improvements in book-holders and leaf-turners; and it has for its objects, among 15 others, to provide a simple and cheap device by which a book may be held open and the leaves turned by a single movement of a key.

The device is light yet strong, can be readily applied in any desired position, and is not 20 liable to get out of order.

Other objects and advantages of the invention will hereinafter appear, and the novel features thereof will be specifically defined by the appended claim.

25 The invention resides in this instance in the peculiar combinations and the construction, arrangement, and adaptation of parts, all as more fully hereinafter described, shown in the drawing, and then particularly pointed 30 out in the claim.

The invention is clearly illustrated in the accompanying drawing, which, with the letters of reference marked thereon, forms a part of this specification, and in which is represented a perspective view of my improved 35 book-holder and leaf-turner.

Referring now to the details of the drawing by letter, A designates the base-piece of the book-holder and leaf-turner. It is designed to be formed of any suitable material 40 and of any desired shape and size. That shown is a convenient one.

B are wires supported from the base-piece, and each wire is bent, as at b, to form the loop 45 a' and then extended at a right angle to the length thereof to form a horizontal arm C and thence substantially parallel with the body portion to form the arm D, which at its lower end is bent upward, as seen at c, and formed 50 with a coil or convolute E, the end of the wire being turned outward and beveled or tapered, as shown. There are two of these wires, one upon each side of the device, as shown, and

the book is designed to be held in the spaces of the free ends thereof and to rest upon the 55 coils or convolutes, as indicated.

The base-piece as well as the wires may be of silver or any desired material and of sufficient strength to support the book. The base-piece may be as ornamental as may be desired.

F are rods mounted for rotation in suitable bearings in the base-piece, being provided at their front ends with keys G, which are secured thereto in any suitable manner, and to 65 the other ends of these rods are secured, preferably detachably, the wires H, each of which is forked or bifurcated, as shown, and in the space between the arms thereof is designed to be received a leaf of the book, which is held 70 by the wires of the holder.

By manipulation of the keys the leaves may be turned, either one or more at a time, either one way or the other, as may be desired.

Modifications in detail may be resorted to without departing from the spirit of the invention or sacrificing any of its advantages.

What is claimed as new is—

As an improved article of manufacture, the 80 book-holder and leaf-turner herein described, comprising the base, the wire supported from said base and said wire upon each side of its center being extended at right angles to said central portion to form a horizontal arm, 85 thence parallel with the body portion to form arms, which are bent outwardly to form horizontal portions and thence downwardly to form depending arms the lower ends of which are bent upward and formed with coils, with 90 the ends of the wires turned outward and tapered, and rods mounted for rotation in the base-piece and provided at their lower ends with keys, and wires detachably secured to the upper ends of said rods and having their 95 upper ends bifurcated to receive a leaf of the book held by the wires of the holder, all substantially as herein shown and described.

In testimony whereof I have signed this specification in the presence of two subscribing witnesses.

DAVID MOON.
